(57) **CLAIM**

I claim the ornamental design for an exercise bench, substantially as shown and described.

DESCRIPTION

FIG. 1 is a front perspective view of an exercise bench showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 shows a front perspective view thereof with dashed lines representing elastic resistance bands as may be used with the exercise bench.

FIG. 10 shows a rear perspective view thereof with dashed lines representing elastic resistance bands as may be used with the exercise bench.

FIG. 11 is a front perspective view of an exercise bench showing my new design;

FIG. 12 is a rear perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof; and,

FIG. 18 is a bottom view thereof.

The dashed lines in the drawings are use for structures to place the invention in context, but do not form part of the claim.
